UNITED STATES PATENT OFFICE.

CHARLES G. DRAESEKE, OF DUNDAS, ONTARIO, CANADA, ASSIGNOR TO NILES-BEMENT-POND COMPANY, OF JERSEY CITY, NEW JERSEY.

CAR-WHEEL LATHE.

972,348.

Specification of Letters Patent.

Patented Oct. 11, 1910.

Application filed May 9, 1910. Serial No. 560,140.

To all whom it may concern:

Be it known that I, CHARLES G. DRAESEKE, a British subject, residing in Dundas, Ontario, Canada, have invented certain new 5 and useful Improvements in Car-Wheel Lathes, of which the following is a specification.

There is a class of lathes for the turning of car wheels while on their axles, the particular class of lathes under consideration being characterized by a longitudinally gapped hollow driving arbor engaging between the two wheels on the axle, the outer end journals of the axle being supported 15 by tailstock bearings. In some forms of lathes of this particular class the tailstocks are transversely gapped so that the journals can pass in and out of the tailstocks when the tailstock spindles are retracted. See, for 20 instance, Stebbins and Sears United States Patent No. 952,084 of March 15th, 1910.

The present invention provides for the lateral insertion and removal of the axle without the need for retracting the tailstock spindles endwise, and the invention 25 will be readily understood from the following description taken in connection with the accompanying drawing in which:—

Figure 1 is a side elevation of a tailstock 30 embodying an exemplification of the invention: Fig. 2 an elevation of the inner end of the tailstock: and Fig. 3 a vertical longitudinal section of the same.

In the drawing:—1, indicates the car- 35 axle: 2, one of its end journals: 3, one of the car wheels on the axle: 4, a segmental bushing engaging the axle-journal and having a tapered exterior engaging toward the car wheel: 5, a flexible spring ring which 40 may, if desired, be employed in holding the segments of the bushing together while permitting their ready application to and removal from the journal when the journal is free of the tailstock: 6, the body of the 45 tailstock: 7, the tailstock bearing: 8, a gap in one of the walls of the tailstock bearing at its inner end, the gap being of sufficient size to permit the free passage through it of the axle-journal with its attached segmental bushing: 9, the tailstock spindle mounted to turn in the tailstock bearing: 10, an inner collar on the tailstock spindle: 11, an outer collar on the tailstock spindle, this latter collar being preferably detach-

ably bolted to the outer end of the tailstock 55 spindle: 12, a gap in one side of the inner end of the tailstock spindle, this gap being of such size as to permit the entry and exit of the axle journal and its bushing, laterally, when the gap in the spindle is brought 60 into coincidence with the gap in the tailstock bearing: 13, a hollow chuck plunger fitted concentrically within the spindle and splined therein and capable of sliding endwise in the spindle: 14, a tapering bore at 65 the front end of the chuck-plunger, this bore fitting the exterior of the segmental bushing: 15, a screw journaled in the outer end of the tailstock spindle and engaging the chuck-plunger and serving as means by 70 which the chuck-plunger may be adjusted endwise: 16, a hand-wheel on this screw: 17, the inner hub of the hand-wheel: 18, an annular tee-shaped slot formed at the outer end of the tailstock spindle, concentrically around screw 15: and 19, a bolt 75 engaging this tee-slot and the hub of the hand-wheel and serving to lock screw 15 in adjusted position.

When work is to be inserted in the lathe, 80 each journal of the axle is to have its segmental bushing placed upon it and the chuck-plungers are to be retracted. The work may now be placed in the lathe, the axle-journals passing through the gaps in 85 the tailstock bearings and their spindles. The hand-wheels are now to be manipulated so as to move the chuck-plungers inwardly toward the car wheels, these plungers engaging the segmental bushings and 90 clamping them closely to the axle journals, after which bolt 19 is to be tightened to prevent the parts working loose. As the wheel and axle-structure is rotated, in the usual operation of the lathe, the tailstock 95 spindles turn in the tailstock bearings, the tailstock spindles forming what might be called artificial journals for the axle.

I claim:—

1. A car wheel lathe of the class referred 100 to comprising, a tailstock bearing having a gap through the inner end of one of its walls, a hollow spindle journaled therein and having a gap through the inner end of its wall, a chuck-plunger fitted to slide axially within the spindle and having at its forward end a flaring bore, a segmental bushing fitting said bore and adapted to engage

an axle-journal, and means for adjusting said chuck-plunger endwise in the spindle, combined substantially as set forth.

2. A car wheel lathe of the class referred to comprising, a tailstock bearing having a gap through the inner end of one of its walls, a hollow spindle journaled therein and having a gap through the inner end of its wall, a chuck-plunger fitted to slide axially within the spindle and having at its forward end a flaring bore, a segmental bushing fitting said bore and adapted to engage an axle-journal, a screw axially journaled in the outer end of the spindle and adapted to turn with the spindle and to be turned independently thereof and threaded into the chuck-plunger, and means for turning said screw, combined substantially as set forth.
3. A car wheel lathe of the class referred to comprising, a tailstock bearing having a gap through the inner end of one of its walls, a hollow spindle journaled therein and having a gap through the inner end of its wall, a chuck-plunger fitted to slide axially within the spindle and having at its forward end a flaring bore, a segmental bushing fitting said bore and adapted to engage an axle-journal, a screw axially journaled in the outer end of the spindle and adapted to turn with the spindle and to be turned independently thereof and threaded into the chuck-plunger, a hand-wheel on the outer end of the screw, and a bolt engaging the inner hub of the hand-wheel and a concentric tee-slot in the outer end of the spindle and serving to lock the screw in adjusted position, combined substantially as set forth.

adapted to turn with the spindle and to be turned independently thereof and threaded into the chuck-plunger, means for turning said screw, and a locking device to lock said screw in adjusted position relative to the spindle, combined substantially as set forth.

4. A car wheel lathe of the class referred to comprising, a tailstock bearing having a gap through the inner end of one of its walls, a hollow spindle journaled therein and having a gap through the inner end of its wall, a chuck-plunger fitted to slide axially within the spindle and having at its forward end a flaring bore, a segmental bushing fitting said bore and adapted to engage an axle-journal, a screw axially journaled in the outer end of the spindle and adapted to turn with the spindle and to be turned independently thereof and threaded into the chuck-plunger, a hand-wheel on the outer end of the screw, and a bolt engaging the inner hub of the hand-wheel and a concentric tee-slot in the outer end of the spindle and serving to lock the screw in adjusted position, combined substantially as set forth.

CHARLES G. DRAESEKE.
